ATHLETIC SHOE SOLE

Joseph P. Famolare, Jr., Florence, Italy, assignor to Famolare, Inc., New York, N.Y.

Filed Feb. 3, 1975, Ser. No. 546,345

Term of patent 14 years

Int. Cl. D2—04

U.S. Cl. D2—320

FIG. 1

FIG. 2

FIG. 3

FIG. 4

FIG. 5

FIG. 1 is a bottom plan view of an athletic shoe sole showing my new design the top being plain and contoured as shown;

FIG. 2 is a near side elevational view thereof;

FIG. 3 is a far side elevational view thereof;

FIG. 4 is a front elevational view thereof; and

FIG. 5 is a rear elevational view thereof.

I claim:

The ornamental design for an athletic shoe sole, substantially as shown and described.
